Section 1-2

Inventor,
George Wright Gregory
By Lachman, Bryant, Wally
Atty.

UNITED STATES PATENT OFFICE.

GEORGE WRIGHT GREGORY, OF LONDON, ENGLAND.

APPARATUS FOR PEELING POTATOES AND THE LIKE.

Application filed December 27, 1921. Serial No. 525,163.

To all whom it may concern:

Be it known that I, GEORGE WRIGHT GREGORY, a subject of the King of Great Britain and Ireland, residing at 128 Putney Bridge 5 Road, Putney, London, S.W., England, have invented certain new and useful Improvements in or Relating to Apparatus for Peeling Potatoes and the like, of which the following is a specification.

- 10 This invention relates to improvements in apparatus for peeling potatoes and the like. My invention has for its object to provide a simple, cheap and efficient apparatus which will carry out the functions named.
- 15 The parts of the apparatus according to my present invention consists of an ordinary wooden handle, a piece of ordinary sheet metal provided with an aperture and so formed as to hold a blade. A safety razor 20 blade may be employed which is split in two, longitudinally, with the cutting edge of the blade slightly protruding through the slit in the sheet metal.

In order that my invention may be fully 25 understood I have appended a sheet of drawings in which:—Figure 1 shews a front view of the peeler. Figure 2 shews a view of the other side thereof, whilst Figure 3 shews an enlarged section on line 1—2 of Figure 1.

30 Referring to the drawings, *a* is a wooden handle. *b* is the sheet metal holder which is formed at the top end with a scoop for removing "eyes" from, say potatoes. *c* is a 35 slit cut in the sheet metal. *d* is an inturned portion, that is to say, a portion curled in,

e is a portion of the sheet metal *b* turned inwardly for the purpose of gripping the blade *f*. *g* is a portion of the sheet metal formed spherical for the purpose of it being secured to the handle *a* by means of the screws 40 *g*¹, *g*².

It will be observed that the holder *b* has its body portion curved inward towards the clamping flange *e* so as to permit the removable blade *f* to effectively peel vegetables or 45 fruits of any irregular formation. While the blade *f* shown in the present disclosure is provided with a double cutting edge, it will be understood that a single edge blade can be as effectively employed with this de- 50 vice.

The section Figure 3, more clearly shews the construction of the portion *b*, turned in portion *d*, turned over portion *e*, blade *f* and the slot *c* in the holder. 55

Claim:

A paring knife of the class described comprising a body having one of its sides bent inward to form a clamping flange and its opposite side inturned to provide a curled 60 portion, said body being curved in concave relation to the clamping flange to effectively permit the peeling of vegetables of irregular formation, a longitudinal slot in said body, and a blade adapted to be removably secured 65 to the body by said clamping flange having one of its edges projecting through said slot for the purpose specified.

GEORGE WRIGHT GREGORY,
